UNITED STATES PATENT OFFICE

MICHEL MILLEVILLE, OF DETROIT, MICHIGAN

METAL WALL CONSTRUCTION

Application filed February 23, 1929. Serial No. 342,075.

My invention relates to a new and useful improvement in a metal wall construction adapted for use in the interior of buildings so as to present a surface which may be easily decorated and which may be easily and quickly cleaned.

It is an object of the present invention to provide in a metal wall construction of this class an arrangement of metal plates which may be easily and quickly mounted in position and which may be secured together in an efficient manner.

Another object of the invention is the provision in a metal wall construction of a securing means whereby the metal plates which are generally used to simulate tile, may be cut to any desired length and the ragged edge effected by the cutting operation, completely concealed from view so as not to mar or effect unsatisfactorily the appearance of the wall.

Other objects will appear hereinafter.

The invention consists in the combination and arrangement of parts hereinafter described and claimed.

The invention will be best understood by a reference to the accompanying drawings which form a part of this specification and in which,

Fig. 1 is a perspective view of a fragment of a wall showing the invention applied.

Fig. 2 is a sectional view taken on line 2-2 of Fig. 1.

Fig. 3 is a fragmentary perspective view illustrating a slightly different form of mold board.

Fig. 4 is a fragmentary perspective view of a mold strip used in the invention.

Fig. 5 is a fragmentary perspective view of another mold strip used in the invention.

Fig. 6 is a fragmentary perspective view of a corner forming mold and baseboard.

Fig. 7 is a view taken on line 7-7 of Fig. 6.

Fig. 8 is a perspective view of a molding strip used in the invention.

In the drawings, I have illustrated the invention applied to a wall and have illustrated a studding 15 extending vertically, to which the metallic plates 16 are secured.

Each of these plates is provided on one edge with spaced tongues 11 and on the opposite edge with the slots 18 adapted for reception of the tongue 17 of an abutting plate. Slots 19 are formed on the upper edge of the plate 17 for the reception of similar tongues which project downwardly from the plate. Extending outwardly from the edges bearing the elongated slots is a flange 20 provided with openings for the reception of nails or other securing means whereby the plate may be attached to the studding 15. By the provision of these flanges and the tongue and slot arrangement, it is evident that the plates when secured to the studding 15 form a rigid construction which is substantially as durable and solid as though the wall were made from a single piece of material. A mold board 21 is used and provided with a channel 22 adjacent its upper inner edge, this channel being formed by the provision of a U-formation, one leg 23 of which is elongated and attached to the studding 15. The projecting tongue 17 of the plate 15 engages in the channel 22 so that the lower edge of the plate is concealed and covered so as to prevent seepage of water thereinto. It will be noted that the arcuate portion of the mold board 21 extends inwardly of the outer face of the plates 16 so that water flowing down the face of the plate is deflected and not permitted to enter the channel 22. The base of the mold board is provided with a channel 24 and also with a U-formation 25 which engages in the channel 26 formed in the U-strip 27, one leg 28 of which is elongated and secured to the studding 15, the other leg engaging in the channel 24, thus securely fastening the mold board to the studding. This method of attachment permits of a quick assembly as the U 27 would, in ordinary construction, be first secured to the studding 15. An arcuate sealing strip 29 is adapted to be secured to the corner as shown in Fig. 1 to cover the edges of the plates 16 and a corner strip 30 is used to cover the end edges of the mold board 21.

In this way there is provided a method of attaching the tile simulating plate 16 so as to

provide a metallic hollow wall construction, these plates being spaced because of their inwardly turned edges, outwardly from the studding 15.

5 In Fig. 3, I have shown a modified form of mold board 34 having a channel 32 in which engages the downwardly projecting tongues of the plates 16, the elongated leg 33 of the U formation of this mold board 10 being secured to the studding 15 in the manner already indicated. The downwardly projecting portion of the mold board which serves as an apron is doubled upon itself as at 35 so as to embrace the upper edge of the tile floor 31, thus affording a means of mounting the metallic hollow wall construction in a 15 bathroom or in a similar place where the tile floor 31 is extended upwardly to provide a base board.

20 In some rooms, particularly in bath rooms, it is desirable to have a tile surface extending part way up the wall and the portion of the wall above the tile surface plastered.

25 In Fig. 4, I have illustrated the invention applied to such a structure, the plates 16 being embraced at their upper edges by the inwardly turned portion 37 of the bead mold 30 which has the upwardly projecting flange 38 which may be secured to the studding 15 and over which may be positioned the layer 39 of plaster which is mounted on the lathes or plaster board 40.

35 In Fig. 5 I have illustrated a mold strip 41 adapted for use at doors, window casings and the like. This mold strip has the inwardly turned portion 42 extending angularly to the angularly extended portion 43 so that the portion 42 engages the studding 15. Secured to the studding 15 is a metallic plate 44 having its outer edge outwardly offset to interlock with the doubled over edge 45 of the lower strip 41. This mold strip may be 40 easily and quickly attached after the strip 44 is in position, screws 41' being projected 45 through the mold strip 41 and serving to bind the mold strip securely in engagement with the studding 15, the doubled over edges of the mold strip 41 serving to provide a spring effect resulting from the resiliency of the metal 50 from which the mold strip 41 is fabricated.

55 In Fig. 6, I have shown a structure for arrangement at corners in which the mold strip 41 is used mounted as described in Fig. 5. The base board 47 is provided with a U 48 at its inner upper edge and an upwardly turned flange 49 at its inner lower edge. The U 48 provides a channel for the reception of the projection portions of the lower edge of the plate 17 and this base board 47 is engaged 60 by the inwardly turned end 50 of a corner block 46 which is secured to the studding 15.

65 In Fig. 8, I have shown a sealing strip 51 which is formed arcuate or angular for resting in a corner and having at its upper end the triangular shaped flange 52, thus serving as

a means for sealing the corner edges of the ceiling.

With a wall construction as described, the advantages sought, particularly economy of erection, saving in labor and durability in use, together with attractiveness in appearance is 70 accomplished.

75 While I have illustrated and described the preferred form of my invention, I do not wish to limit myself to the precise detail of structure shown but desire to avail myself of such variations and modifications as come within the scope of the appended claims.

Having thus described my invention, what I claim as new and desire to secure by Letters Patent is:

1. In a construction of the class described, a metallic mold board having one of its edges doubled upon itself to provide a structure U shaped in cross section, one of the legs of said U shaped structure being extended and adapted for being secured to a supporting body; a double U shaped construction at the opposite edge of said mold board one of said U shaped formations opening outwardly and the other opening inwardly of said mold board.

85 2. In a construction of the class described, a metallic mold board having one of its edges doubled upon itself to provide a structure 90 U shaped in cross section, one of the legs of said U shaped structure being extended and adapted for being secured to a supporting body; a double U shaped construction at the opposite edge of said mold board one of said U shaped formations opening outwardly and the other opening inwardly of said mold board; and a U shaped retaining clip mounted 95 on said supporting body for receiving the outermost of said U shaped formations and retaining said mold board in fixed relation to 100 said supporting body.

105 In testimony whereof I have signed the foregoing specification.
